CLAIM

The ornamental design for a metal pan, as shown and described.

DESCRIPTION

FIG. 1 is a top perspective view of a metal pan, showing my new design;

FIG. 2 is a bottom perspective view thereof;

FIG. 3 is a front elevational view thereof, the rear elevational view is identical;

FIG. 4 is a left side view thereof, the right side view is identical;

FIG. 5 is a top perspective view;

FIG. 6 is a bottom plan view thereof; and,

FIG. 7 is a sectional view of 7-7 along the line in FIG. 3. The broken lines in the figures are for the purposes of illustrating portions of the metal pan, which form no part of the claimed design.
